UNITED STATES PATENT OFFICE.

SAMUEL LOAFEA, OF OAKLAND, CALIFORNIA.

CORRUGATING MACHINE.

Application filed July 5, 1923. Serial No. 649,483.

To all whom it may concern:

Be it known that I, SAMUEL LOAFEA, a citizen of the United States, and a resident of Oakland, county of Alameda and State of California, have invented a new and useful Corrugating Machine, of which the following is a specification.

My invention relates to a corrugating machine, particularly adapted for corrugating sheet metal.

An object of the invention is to provide a sheet-metal corrugating machine which is adapted upon the application of a slight effort to instantly exert a powerful force on the work or release the application of such force.

Another object of my invention is to provide a corrugating machine which may be adjusted to maintain any desired relationship between the corrugating rolls regardless of their distance apart.

A further object is to provide a machine of the character described in which the pressure exerted by the rolls on the work may be evenly distributed throughout the length of the rolls.

A still further object of my invention is to provide a machine of the character described in which the relationship between the corrugating rolls may be entirely controlled through a lever operable with one hand.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:—

Figure 1 is a side view of the corrugating machine of my invention.

Fig. 2 is an end view of the machine.

Fig. 3 is an enlarged sectional view of a portion of my device taken on the line 3—3 in Fig. 1.

Fig. 4 is an enlarged sectional view of the device taken on the line 4—4 in Fig. 2.

Briefly expressed the corrugating machine of my invention in its present embodiment comprises a frame having a fixed rotatable

pressure roll and an adjustable rotatable pressure roll whose shaft is mounted in slideable bearings. A pair of levers is fulcrumed on the frame and operatively and adjustably connected at one end to stems attached to said bearings, springs being arranged about the stems so as to resiliently hold said rolls apart. Movement of the rolls toward each other is effected by means of a hand lever which is fulcrumed to the frame and is provided with a cam portion arranged to engage a guided slideable block to which the other ends of said levers are connected. The adjustable roll may be held positively and locked in various desired positions. Driving of the pressure rolls is effected by gears which are adapted to remain in engagement regardless of the position of the adjustable roll.

A detailed description follows:—

The machine of my invention in its present embodiment is particularly adapted for corrugating flat sheets of metal or sheets bent to cylindrical or other forms. As illustrated, the machine comprises a frame 5 having a post 6 from which upper and lower arms 7 and 8 extend transversely. Mounted in bearings 10 and 11 carried in the frame between the arms is a pair of shafts 12 and 13. The bearings 11 are preferably held fixed in the frame, while the bearings 10 are slidably held in guideways 14 to enable the shaft 12 to be moved transversely to and from the shaft 13. Removably mounted on the shafts 12 and 13 for rotation therewith are corrugating rolls 15 and 16 respectively, which are here shown fluted longitudinally and grooved circumferentially.

Fixed to the movable bearings 10, which bearings it will be noted are disposed at opposite ends of the rolls, are vertical studs or stems 18 which extend through and above the frame. The rolls are resiliently held apart by means of springs 19 encircling the stems and interposed between the top of the frame and a nut 21 adjustably held on the stem.

Means are provided for causing both stems to be simultaneously depressed. Fulcrumed on the frame to swing in a plane parallel to the plane of movement of the roll 15 with respect to roll 16 is a pair of levers 22, one arm 23 of each of which is adapted to operatively engage the stems 18. In the present embodiment of the invention, engagement between the levers and stems

is effected by means of shoes 24 formed on the arms 23 arranged to rest in recesses 26 formed in nuts 27 which engage the threaded portion 28 of the stem. It will be noted 5 that the positioning of the nut 27 on the stem determines the effective length of the stem and thus affords an adjustable relationship between the stems and levers. The other arms 29 of the levers are connected 10 to a slidable block or cross-head 31 by means of links 32. The block is guided for movement corresponding with that of the slid- 15 able roll by means of bars 33 fixed to the frame and engaging in suitable bores pro- vided in the block.

Fulcrumed on the frame is a hand lever 34 one arm of which is in the form of a cam member 36 which is preferably arranged to engage a roller 37 carried on the 20 block 31. Thus, by pulling the lever and elevating the block, motion will be communicated to the stems through the intermediate links 32 and levers against the resistance of the springs 19. By the use of 25 the foregoing construction it will be clearly understood that a slight force applied to the lever handle 38 will cause the instant application of a powerful force to the metal which may be interposed between complementary parts of the rolls.

Means are provided for holding the adjustable roll in any desired position with respect to the fixed roll. As here shown, such means includes a pawl 41 carried by 35 the hand lever and arranged to engage a ratchet 42 which is adjustably secured to the movable block. The pawl is preferably associated with a spring 43 which tends to keep the pawl in engagement with the ratchet. The pawl may be released from the 40 ratchet by suitably pulling on a chain 44 after slightly depressing the hand lever.

Power for rotating the rolls is preferably transmitted through a clutch 46 to 45 a drive gear 47 fixed on the shaft 13. The motion of the gear 47 is transmitted to a gear 48 fixed on the shaft 12 by means of a pair of idler gears 49 and 50 mounted on fixed stub shafts carried on the post 6. The 50 engagement of the gears 48 and 49 is such as to allow the vertical movement of the gear 48 without destroying their operative engagement. As here shown, the gear 48 is arranged to be moved tangentially across 55 the face of the gear 49, so that considerable movement in its path is allowed without getting the gear entirely out of mesh, the movement of the roller shaft 12 relative to the shaft 13 being limited to main- 60 tain the meshed relation of the gears.

In the operation of the device, with the 65 rolls suitably separated, the metal to be corrugated is inserted between the rolls. The hand lever is then depressed until the pawl engages in the desired ratchet notch,

the ratchet member having been previously adjusted on the block to afford the desired positioning of the roll 15, thus initially forming the metal immediately between the rolls with the desired corrugation. By then 70 throwing in the clutch, power is applied to rotate the rolls to advance and corrugate the sheet. As soon as the corrugating operation is completed, the pawl may be withdrawn from the ratchet to enable separating 75 of the rolls and removal of the work.

I claim:

1. In a corrugating machine, a frame, a rotatable corrugating roll mounted in said frame, a complementary corrugating roll 80 mounted to move toward and from said first roll, levers fulcrumed on the frame connected to said second roll, means operatively connecting said levers, and a hand lever fulcrumed on said frame provided 85 with a cam portion adapted to engage said means to rock said first levers.

2. In a corrugating machine, a frame, a rotatable corrugating roll mounted in said frame, a complementary corrugating roll, 90 bearings at each end of said second roll slidably mounted in said frame to permit movement of said roll toward and from said first roll, levers operatively connected to said bearings and fulcrumed on said frame to swing parallel to the plane of movement of said second roll, and means including a cam member for rocking said levers simultaneously.

3. In a corrugating machine, a frame, a rotatable corrugating roll fixedly mounted in said frame, a complementary corrugating roll, 100 slideable bearings at each end of said second roll for enabling the latter to move toward and from the first roll, stems 105 extending from said bearings, levers fulcrumed on the frame having one of the arms thereof arranged to bear on said stems, a cross-head mounted on the frame, links connecting said cross-head to the 110 other arm of said levers, and means for moving said cross-head.

4. In a corrugating machine, a frame, a rotatable corrugating roll fixedly held in said frame, a complementary rotatable corrugating roll, slideable bearings at each end of said second roll for enabling the latter to move toward and from the first roll, stems attached to said bearings and extending through the frame, springs encircling 115 said stems and arranged to yieldingly urge said second roll from said first, levers fulcrumed on the frame adapted to swing in a plane defined by the movement of said second roll, one of the arms of said levers being arranged to operatively engage said stems, means including a cross-head for connecting the other ends of said levers together, and a lever-operated cam for moving 120 said cross-head.

125
130

5. In a corrugating machine, a frame, a rotatable corrugating roll fixedly held in said frame, a complementary rotatable corrugating roll mounted to move toward and from said first roll, levers fulcrumed on the frame and having one of their arms connected to the opposite ends of said second roll, a slidable member connected to the other arms of said levers, means for guiding said slidable member in a plane corresponding to the plane of movement of said second roll relative to the first, and manually operated means for moving said slidable member.
10. In a corrugating machine, a frame, a rotatable corrugating roll held in said frame, a complementary rotatable corrugating roll, slidable bearings carrying said complementary roll in said frame, means for resiliently urging said rolls apart, means including a lever for moving said second roll with respect to the first against said resilient resistance, and means associated with said lever for locking said rolls in different relative positions.
15. In a corrugating machine, a frame, a rotatable corrugating roll held in said frame, a complementary rotatable corrugating roll mounted for movement toward and from said first roll, levers fulcrumed on the frame and having one of their arms connected to the opposite ends of said second roll, a slidable member connected to the other arms of said levers, a ratchet member
20. adjustably secured to and movable with said slidable member, a lever for moving said slidable member in one direction, means resiliently urging said slidable member in the opposite direction, a pawl carried by said last named lever and arranged to engage said ratchet, and means for releasing said pawl from engagement with said ratchet.
25. In a corrugating machine, a frame, a rotatable corrugating roll held in said frame, a complementary rotatable corrugating roll, slidable bearings carrying said complementary roll and carried on said frame, stems secured to said bearings, levers fulcrumed on the frame having one arm
30. operatively connected to each of said stems, said levers being movable in a plane parallel to the plane of movement of the second roll relative to the first, a block guided for
35. movement in a plane parallel to said first plane, links connecting said block to the other arms of said levers, a roller carried by said block, a lever fulcrumed on the frame, having a cam portion arranged to engage said roller, a ratchet adjustably fixed to said block, and a pawl arranged to engage said ratchet.
40. In a corrugating machine, a frame, a rotatable corrugating roll held in said frame, a complementary rotatable corrugating roll, slidable bearings carrying said complementary roll and carried on said frame, stems secured to said bearings, levers fulcrumed on the frame having one arm
45. operatively connected to each of said stems, said levers being movable in a plane parallel to the plane of movement of the second roll relative to the first, and manually operated means for moving said slidable member.
50. In a corrugating machine, a frame, a rotatable corrugating roll held in said frame, a complementary rotatable corrugating roll, slidable bearings carrying said complementary roll and carried on said frame, stems secured to said bearings, levers fulcrumed on the frame having one arm
55. operatively connected to each of said stems, said levers being movable in a plane parallel to the plane of movement of the second roll relative to the first, and manually operated means for moving said slidable member.
60. In a corrugating machine, a frame, a rotatable corrugating roll held in said frame, a complementary rotatable corrugating roll, slidable bearings carrying said complementary roll and carried on said frame, stems secured to said bearings, levers fulcrumed on the frame having one arm
65. operatively connected to each of said stems, said levers being movable in a plane parallel to the plane of movement of the second roll relative to the first, a block guided for
70. movement in a plane parallel to said first plane, links connecting said block to the other arms of said levers, a roller carried by said block, a lever fulcrumed on the frame, having a cam portion arranged to engage said roller, a ratchet adjustably fixed to said block, and a pawl arranged to engage said ratchet.
75. In a corrugating machine, a frame, a rotatable corrugating roll held in said frame, a complementary rotatable corrugating roll, slidable bearings carrying said complementary roll and carried on said frame, stems secured to said bearings, levers fulcrumed on the frame having one arm
80. operatively connected to each of said stems, said levers being movable in a plane parallel to the plane of movement of the second roll relative to the first, a block guided for
85. movement in a plane parallel to said first plane, links connecting said block to the other arms of said levers, a roller carried by said block, a lever fulcrumed on the frame, having a cam portion arranged to engage said roller, a ratchet adjustably fixed to said block, and a pawl arranged to engage said ratchet, a driving gear axially aligned and fixed for
90. rotation with said fixedly mounted roll, a driven gear axially aligned and fixed for rotation with said second roll, and a pair of idler gears arranged to operatively connect said drive and driven gears in all the positions of said second roll with respect to the first.
95. In a corrugating machine, a frame, a rotatable corrugating roll fixedly mounted in said frame, a complementary rotatable corrugating roll, slidable bearings carrying said complementary roll for movement toward and from said first roll, levers fulcrumed on the frame, adjustable means connecting one end of the arms of said levers
100. to the bearings of said second roll, a slid- able block member connected to the other arms of said levers, means for guiding said slidable block for reciprocation in the plane of movement of said second roll relative to the first, and manually operated means for moving said slidable member.

In testimony whereof, I have hereunto set my hand at Oakland, this 12th day of June, 1923.

SAMUEL LOAFEA.
